WILLIAM F. DRAPER, OF HOPEDALE, MASSACHUSETTS; CLARE H. DRAPER AND OLIVER H. LANE EXECUTORS OF SAID WILLIAM F. DRAPER, DECEASED.

FILLING-REPLENISHING LOOM.

973,265.

Specification of Letters Patent. Patented Oct. 18, 1910.

Application filed March 24, 1909. Serial No. 485,878.

To all whom it may concern:

Be it known that I, WILLIAM F. DRAPER, a citizen of the United States, residing at Hopedale, in the county of Worcester and 5 State of Massachusetts, have invented an Improvement in Filling-Replenishing Looms, of which the following description, in connection with the accompanying drawings, is a specification, like characters on the drawings representing like parts.

The invention to be hereinafter described relates to filling replenishing looms wherein a fresh supply of filling is furnished at desired times.

15 The aims and objects of the present invention are more particularly to provide means for controlling the filling ends which lead from the filling carriers as they progressively move to the transferring position, and these 20 matters will best be understood from the following description and drawings of one form or embodiment of means for carrying the invention into practical effect, it being understood that the invention is not limited 25 nor circumscribed by the details of structure illustrated and described, but in its true scope is definitely set forth in the claims.

In the drawings: Figure 1 is an end elevation of the filling replenishing side of so 30 much of a loom as is desirable for showing the relation of the present invention with the associated parts; Fig. 1^a is a detached detail of the hopper; Fig. 2 is a front elevation of the parts shown by Fig. 1, some of 35 said parts being omitted for clearness; Fig. 3 is a sectional plan view on line 3—3 of Fig. 2; Fig. 4 is a detached detail elevation, partly in section, looking in the direction of the arrow, Fig. 6; Fig. 5 is a section on the 40 line 5—5, Fig. 4; and Fig. 6 is a detached detail side elevation of one form of filling end controller embodying the present invention.

The loom frame A; the breast beam B; 45 the lay C; the transverse shaft D; the finger E secured thereto and adapted to be operated by the usual means well understood in the art; the transerrer dog F pivoted to the arm H of the transerrer; the 50 transerrer I and the bunter G for actuating the transerrer through the dog F, in the manner well understood by those skilled in

the art, may be of any usual or desired character and need no further description.

Mounted upon suitable brackets 1, Figs. 1, 55 2 and 3, supported from the loom frame is the shaft 2 to which is secured the disks 3, 4 having suitable receiving portions, as 5, 6, Fig. 3, for the base and tip of filling carriers 7, which may be of any usual type employed in such looms. Extending upward from the group of carriers 7, which are positioned by the disks or separating arms 3, 4 for transfer to the shuttle beneath, is a 60 hopper 8, Figs. 1 and 2. This hopper may 65 be of any usual or desired character and is adapted to support a column of filling carriers, as indicated in Fig. 2, said filling carriers gradually moving downward in the hopper 8 into position to be engaged and 70 separated from each other by the disk elements 3, 4, said disk elements being of any desired character to properly separate the filling carriers as they move to the transferring position, as indicated in Fig. 3. 75

The hopper 8 is provided with a slot 9 extending the full height of the hopper, and when a charge of filling carriers is placed in the hopper the filling ends 10 leading therefrom, Figs. 2 and 3, are passed 80 through the slot 9 and so held that when a carrier has reached transferring position over the shuttle, and is transferred, in the usual manner, by the transferring mechanism, the filling end leading from the carrier will be in such position that on movement of the shuttle the filling will be drawn 85 from the filling carrier and the shuttle be enabled to assume deliverable control of the filling. It is desirable to so hold the filling 90 ends relative to the top of the shuttle box that the filling between the carrier and the held end will be in position to be engaged by the shuttle so that, when the shuttle moves, the filling may pass into the usual 95 threading mechanism of the shuttle and be thereafter controlled in its delivery from the filling carrier, as well understood by those skilled in the art. As the filling carriers move downward in the hopper 8, it is 100 evident that the filling ends 10 from said filling carriers, if held at a point exterior to the hopper and adjacent its lower portion, will gradually become slack if no means

is provided for taking up such slack, and slackness is liable to occur in individual filling ends by turning of the carrier in the hopper, or for other reasons. This slack 5 in the filling extending between the carrier and the held end is objectionable, as will be well understood by those skilled in the art, and means are contemplated by the invention for overcoming this objection and at the 10 same time for holding the filling ends in the desired position relative to the shuttle box and shuttle, as will now be described.

Mounted on the shaft 2, Figs. 2 and 3, which is extended from the brackets 1, and 15 suitably supported by a bracket arm 11, is a wheel 12, having a roughened or felt covered surface 13. Mounted on the bracket arm 11 and depending therefrom is a stem 14, Figs. 4, 5 and 6, carrying at its lower 20 end a roughened surfaced roll 15 normally held in engagement with the wheel 12 by means of a spring 16 interposed between a guide bracket 17 supported from the bracket arm 11 and an adjustable collar 18 25 mounted on the stem 14 and secured thereto in adjusted position by means of a set screw 19, said stem being guided in its movement responsive to the spring 16 by means of the guide bracket 17 and a similar guide bracket 30 20 near the upper end of said stem 14, the construction being such that the roll 15 is normally held by the yielding action of the spring 16 in engagement with the wheel 12, as will be readily understood from Figs. 4, 35 5 and 6. Depending from or supported by the bracket arm 11 is a guide piece 21, said guide piece preferably, though not necessarily, carrying the guide brackets 17 and 20, as indicated, and terminating at its rear 40 portion with a guiding edge 22 furnishing a recess or shoulder 23 and a further depending part 24. In order that the roll 15 may be further guided in its movement toward and from the wheel 12, the guide piece 45 21 may be provided at its lower portion with a frontwardly extending table part 26, as shown in Figs. 5 and 6, and said part 26, together with the part 24, may be provided with slots 25 into which the supporting 50 journals of the roller extend. The ends 10 of the filling, leading from the filling carriers in the hopper and from the filling carriers controlled by the filling carrier separator 3 and 4, are taken together or bunched 55 and passed, as indicated in Fig. 1, under the shouldered part 23 of the piece 21 and then between the wheel 12 and the roll 15, the ends of said filling, if desired, being then directed over an arm or support 27, Figs. 60 1, 2 and 3.

From the construction described as one form of the invention, regardless of the character of the hopper, or of the filling carrier separator or of the transferring mecha-

nism associated therewith, it will be evident 65 that, upon movement of the carriers downward in the hopper and the consequent rotation of the filling carrier separator 3, 4, the wheel 12, will be rotated and take up any undesirable slack that may be formed 70 in the portion 10 of the filling between the filling carrier and bite of the roll 15 and wheel 12. If the surface movement of the take-up rolls is the same as the movement of the filling carriers toward transferring position, which will be the case when the size 75 of the wheel or roll 12 is the same as the separator 3, 4, it is evident that all slack filling produced by movement of the carriers to transferring position will be taken up by 80 the means described. If, on the other hand, the surface movement of the take-up rolls is greater than the movement of the filling carriers toward transferring position, which will be the case, in the illustrated form of 85 the invention, when the wheel or roll 12 is larger than the separator 3, 4, then there will be a relative slip of the roll surface over the bunch of filling ends, which will cause the roll surface to act upon any individual filling end that may have become slack by turning of its carrier in the hopper or otherwise, and take up such individual slack.

In the present embodiment of the invention the filling carrier separator 3, 4 has been illustrated as of a rotary character, therefore, as the filling carriers come down the hopper 8 and are engaged by the filling carrier separator, they move downward to 100 transferring position on the arc of a circle so that the slot 9 in the hopper 8, where it guides the filling ends adjacent the filling carrier separator, is curved on the arc of a circle, as indicated at 28, Fig. 1, it being 105 understood that at this portion of the hopper the edge of the bracket 1, as indicated in Fig. 3, may serve as one wall of the guiding slot 9.

Obviously the invention is not circumscribed by the character of the filling carrier separator or by its rotary movement, nor is it limited to any special means for actuating the wheel 12, it being understood that the invention is generic in character, 110 as pointed out in the claims. It will also be obvious to those skilled in the art that the wheel 12 and its coöperating roll 15 may be differently disposed and differently formed, within the true scope of the invention, as applicant believes he is the first to provide in a filling replenishing loom any means actuated for progressively taking up the slack of the filling ends extending from the filling carriers as they move 115 120 125 in procession toward the transferring position.

The separating elements 3, 4 by which

the filling carriers are directed to transferring position may be formed either as part of a filling feeder wherein the filling carriers would be held, or they may be formed merely as positioning members to separate and position the filling carriers as they move by gravity into transferring position. In any aspect of the case the invention herein is intended to be unlimited by the character of the separating or positioning elements.

When the hopper is formed with a slot 9 for the filling ends, the walls of the slot are liable to come together under some conditions and clamp or otherwise interfere with the filling ends leading therethrough. This is especially the case where the hopper is formed of light material, or is made to hold a large number of filling carriers, but, obviously, regardless of size or details of structure, any great vibration of the loom or carelessness on the part of the operatives will be liable to cause one part of the hopper to be deflected from its true position and close the slot 9. On the other hand, it is essential that the slot be maintained in such condition as not to interfere with the proper descent of the filling ends as the filling carriers move in procession to transferring position and as the filling end take-up acts, as described. The present invention contemplates means to maintain the slot 9 in normal open position at all times and yet not interfere with the convenient loading of the hopper. As one form of such means, one of the side walls of the hopper, preferably near its upper portion, is provided with a slot closing preventer one simple form of which is shown as a lug or projection 90 formed on or connected to one wall of the hopper and extending toward the opposite wall of the slot 9, the construction being such that any vibration or shock tending to close the slot 9 and thereby clamp, break, or otherwise interfere with the proper delivery of the filling end will be prevented, as will be readily understood.

As hereinbefore noted the form and general character of the take-up for acting upon the filling ends leading from the filling carriers in the hopper may be variously changed or modified and may be actuated by any suitable means to take up the slack in the filling ends. In the form of the invention illustrated, the take-up is actuated by the movement of the filling carriers toward transferring position, and while this is found to be one convenient way for operating the take-up, yet it is to be understood that the invention contemplates actuation of the take-up by any means and obviously also the speed of take-up may be changed, as for instance by changing the size of the take-up wheels, or altering the action of

the actuating means that may be employed in any particular case. In all these respects the invention is generic, regardless of the particular means employed to operate the take-up device for the filling ends, or the fact that the take-up movement is relatively the same in amount as or different from the movement of the filling carriers toward transferring position, or the character of the means for acting on the filling carriers to put them successively into transferring position or to transfer them to the shuttle, and is clearly defined by the claims.

What is claimed is:

1. In a filling replenishing loom, the combination of a lay, a shuttle box, filling carrier transferring mechanism, rotary means to direct a series of filling carriers to transferring position, and means actuated from said rotary means to draw the filling longitudinally and take up the slack of the filling ends as the carriers move to transferring position.

2. In a filling replenishing loom, the combination of filling carrier transferring mechanism, means for supplying a series of filling carriers to be transferred, means for taking up the slack in the filling by drawing it longitudinally as the carriers move toward the transferring position, and actuating devices for said means.

3. In a filling replenishing loom, the combination of transferring mechanism, means for supplying a series of filling carriers to be transferred, means to take up the slack filling as the carriers move toward transferring position, and devices effective as the carriers move to operate said means.

4. In a filling replenishing loom, the combination of transferring mechanism, a hopper for supplying filling carriers to said mechanism, means operative on movement of the filling carriers to take up the slack filling as the filling carriers move to transferring position, and operating devices therefor.

5. In a filling replenishing loom, a source of filling carrier supply, a transferrer to transfer a filling carrier to a shuttle, a surface over which the filling ends leading from the carriers in the supply pass, and means for moving said surface to cause it to take up the slack occurring in the filling ends.

6. In a filling replenishing loom, a source of filling carrier supply, a transferrer to transfer a filling carrier to a shuttle, and rotary means acting upon a portion of the filling extended from the carrier to take up the slack filling as the carrier moves to transferring position.

7. In a filling replenishing loom, the combination of a hopper adapted to contain a series of filling carriers, and provided with a slot for the ends of the filling extended from said hopper, and rotary means to take

up slack produced in the extended portion of said filling as the carriers move in the hopper.

8. In a filling replenishing loom, the combination of a hopper adapted to contain a series of filling carriers, a transferer, a rotary element to separate the carriers and cause them to be directed to the action of the transferer, and means actuated by movement of the rotary element to take up slack in the filling extended from the carriers.

9. In a filling replenishing loom, the combination of a source of filling carrier supply, transferring mechanism for transferring a filling carrier furnished by said supply, a positively acting take-up for taking up slack produced in the filling ends leading from the carriers in the supply, and mechanism for imparting to the take-up positive take-up movement.

10. In a filling replenishing loom, the combination of a transferer, a source of filling carrier supply, means to direct the filling carriers to the action of said transferer, and means actuated by the said directing means to take up slack in the filling extended from the filling carriers.

11. In a filling replenishing loom, the combination of a transferer, a source of filling carrier supply, rotatable means for directing the filling carriers to the action of the transferer, and a filling end controller movable by said rotatable means for taking up the slack in the filling extended from the filling carriers.

12. In a filling replenishing loom, the combination of a transferer, a source of filling carrier supply, means for directing the filling carriers to the action of the transferer, a filling controller, an element between which and said controller the filling ends extend, and means for actuating the controller to move the filling ends.

13. In a filling replenishing loom, the combination of a transferer, a source of filling carrier supply, a wheel and roll between which the filling ends leading from the carriers pass, and means for holding said wheel and roll in operative relation.

14. In a filling replenishing loom, the combination of a transferer, a source of filling carrier supply, a wheel and roll between which the filling ends pass, and means for rotating one of said parts to cause them to draw upon and take up the slack in the filling ends.

15. In a filling replenishing loom, a hopper having a chamber for containing filling carriers, an end wall of said chamber being provided with a slot for the passage of filling ends extending from the carriers in the chamber, and a slot closing preventer comprising a projection formed on one wall of

the hopper on one side of the slot and extending toward the opposite wall of the slot and arranged to permit the filling ends to be introduced into the slot from the top of the hopper and acting to prevent the walls of the slot from being closed on the filling ends that the filling carriers may move successively to transferring position with intact filling leading therefrom.

16. In a filling replenishing loom, the combination of a hopper adapted to contain a series of filling carriers and provided with a slot for the ends of the filling extended from the hopper, a slot closing preventer to maintain the slot open for the free passage of the filling end, and means for taking up the slack in the extended ends of the filling as the carriers move in the hopper.

17. In a filling replenishing loom, the combination of filling carrier transferring mechanism, means for supplying filling carriers to be transferred, means for positively drawing the filling ends longitudinally to take up the slack in the filling, and operating mechanism for said means.

18. In a filling replenishing loom, the combination of filling carrier transferring mechanism, means for supplying filling carriers thereto, means for taking up the slack filling as the carriers move toward transferring position, a guide for directing the filling ends to said means, and a support for the filling ends after they pass from the action of said means.

19. In a filling replenishing loom, the combination of a filling carrier supply, transferring mechanism for transferring filling carriers furnished by said supply, two surfaces between which the filling ends pass, and means for moving one of said surfaces to take up slack in the filling ends.

20. In a filling replenishing loom, the combination of a filling carrier supply, transferring mechanism for transferring filling carriers furnished by said supply, a take-up for acting on a plurality of filling ends extended from the filling carriers, and means for operating the take-up.

21. In a filling replenishing loom, the combination of a filling carrier supply, means for transferring a filling carrier furnished by said supply, a take-up, and means for causing it to take up slack in a plurality of filling ends and also slack occurring in any individual filling end.

22. In a filling replenishing loom, the combination of a hopper, filling replenishing means, a take-up and means for operating the take-up to cause it to act upon a plurality of filling ends and also to take up the slack occurring in any individual filling end.

23. In a filling replenishing loom, the combination of a filling carrier supply, filling carrier transferring means, a take-up

having a surface for acting on a plurality of filling ends extended from the carriers, and means for moving said surface to cause it to take up slack occurring in the plurality of filling ends produced as the carriers move toward transferring position and to take up any extra slack that may occur in any individual filling end. 5

In testimony whereof, I have signed my name to this specification, in the presence of 10 two subscribing witnesses.

WILLIAM F. DRAPER.
